US00D862008S

(12) **United States Design Patent** (10) **Patent No.:** **US D862,008 S**
Penland (45) **Date of Patent:** **** Oct. 1, 2019**

(54) **TREATMENT APPLICATOR**

(71) Applicant: **Brandon Penland**, Linwood, NJ (US)

(72) Inventor: **Brandon Penland**, Linwood, NJ (US)

(**) Term: **15 Years**

(21) Appl. No.: **29/662,852**

(22) Filed: **Sep. 10, 2018**

Related U.S. Application Data

(63) Continuation of application No. 29/587,586, filed on Dec. 14, 2016, now Pat. No. Des. 828,653.

(57) **CLAIM**

The ornamental design for a treatment applicator, as shown and described.

DESCRIPTION

FIG. 1 is an isometric view of the treatment applicator; FIG. 2 is a top view of the treatment applicator; FIG. 3 is a bottom view of the treatment applicator; FIG. 4 is a left view of the treatment applicator; FIG. 5 is a right view of the treatment applicator; FIG. 6 is a back view of the treatment applicator; FIG. 7 is a front view of the treatment applicator; and, FIG. 8 is another isometric view of the treatment applicator. The broken lines depict unclaimed features of the treatment applicator that form no part of the design claim but are shown for purposes of illustration.

1 Claim, 7 Drawing Sheets
